CLAIM

The ornamental design for a skid steer loader, as shown and described.

DESCRIPTION

FIG. 1 is a perspective view of the skid steer loader according to the invention;
FIG. 2 is a front elevation view of the skid steer loader of FIG. 1;
FIG. 3 is a rear elevation view of the skid steer loader of FIG. 1;
FIG. 4 is a right side elevation view of the skid steer loader of FIG. 1;
FIG. 5 is a left side elevation view of the skid steer loader of FIG. 1; and,
FIG. 6 is a top plan view of the skid steer loader of FIG. 1. The broken line showing of the skid steer loader is for the purpose of illustrating portions of the skid steer loader and forms no part of the claimed design.

1 Claim, 6 Drawing Sheets
